UNITED STATES PATENT OFFICE.

RAY C. NEWHOUSE, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

CRUSHER-MANTLE.

1,151,119.

Specification of Letters Patent. Patented Aug. 24, 1915.

Application filed December 8, 1913. Serial No. 805,869.

To all whom it may concern:

Be it known that I, RAY C. NEWHOUSE, a citizen of the United States, residing at Milwaukee, in the county of Milwaukee and 5 State of Wisconsin, have invented a certain new and useful Improvement in Crusher-Mantles, of which the following is a specification.

This invention relates to improvements in 10 the construction of crusher mantles, and more specifically to means for automatically locking the crusher mantles of gyratory crushers or similar devices, to their supporting elements.

15 An object of the invention is to provide simple and effective means for automatically locking or securing the mantles of crushers to their supporting heads or elements.

More specifically, the invention relates to 20 the construction of a tapered mantle for gyratory crushers, with a helical end surface or its equivalent, at its smaller end, this end surface being adapted for coaction with an adjacent element whereby upon relative 25 rotation of the mantle the same is automatically forced onto its supporting member.

Another object of the invention is to provide means for automatically locking or 30 tightening the mantle of a crusher to its supporting member during relative rotation of the crusher mantle in either direction, this result being attained in applicant's device by compounding the end surfaces and 35 forming them of opposite pitch or inclination relative to a plane perpendicular to the crusher axis.

The present invention is applicable either to a unitary mantle in which the mantle is constructed entirely of one piece, or to a 40 sectional mantle in which the mantle is formed of a series or plurality of individual mantles.

A clear conception of an embodiment of 45 the invention may be had by referring to the drawing accompanying and forming a part of this specification in which like reference characters designate the same parts in the various views.

Figure 1 is a top view of a gyratory 50 crusher head center and mantle, showing the suspension shaft thereof in section. Fig. 2 is a side elevation of the crusher head disclosed in Fig. 1. Fig. 3 is a transverse cen-

tral vertical section through the crusher head and mantle disclosed in Figs. 1 and 2. 55

The crusher head center 2 which may be formed integral with the shaft 1, is secured to the tapered portion of the main crusher shaft 1 by means of a series of keys 3. The outer surface of the head center 2 is tapered 60 or conical in shape, converging upwardly. The lower and upper mantles 4, 5, respectively, are fitted upon the outer tapered surface of the head center 2 and are formed with inclined or helical surfaces 12, 13, or 65 their equivalents, at their upper ends respectively. In order to facilitate description of the invention, the surfaces 12, 13, will be designated as helical surfaces, but it should be understood that this term is intended to 70 include all forms of surfaces which will cause the elements coacting along these surfaces to separate or move away from each other upon relative rotation of one of these elements. The helical surfaces 12 at the 75 upper end of the lower mantle 4 are formed directly on the mantle and coact with correspondingly formed helical surfaces 12 at the lower end of the mantle 5. The helical surfaces 13 at the upper end of the mantle 80 5, as disclosed, are formed on a separate ring 6 which is firmly fixed to the upper mantle 5 by means of keys 11 or other suitable locking means. The surfaces 13 may, however, be formed directly on the mantle 5 if so 85 desired.

The helical surfaces 13 at the upper and smaller end of the mantle 5 coact with similar surfaces formed on the ring 7. The ring 7 is locked against rotation relative to the 90 main shaft 1 by means of keys or other suitable locking means 10. The ring 7 is prevented from moving upwardly along the shaft by means of a ring nut 8 which coacts with screw threads 9 formed on the shaft 1 95 and which is adjustable along the shaft 1 by the insertion of a suitable instrument within the recesses or notches 14. The ring nut 8 is normally locked in position by means of the usual lock nut, not shown, 100 which coacts with the upper threads 9 and with the upper surface of the nut 8. The helical surfaces 12, 13, are compounded, some of the surfaces being of opposite pitch from others. As disclosed, the upper end 105 of each of the mantles 4, 5, is provided with

two helical surfaces having similar pitch, and two intersecting helical surfaces having opposite pitch or inclination relative to planes perpendicular to the crusher axis.

5 During assembling of the crusher head the head core or center 2 is first fitted to and fixed upon the main shaft 1. The interior surfaces of the mantles 4, 5, are then ground or otherwise formed to snugly fit the outer 10 surface of the head center 2. After being properly fitted to the head center 2, and after having had their upper inclined or helical surfaces 12, 13, fitted to coact with the correspondingly shaped surfaces of the 15 adjacent elements, the mantles 4, 5, are placed over the head center 2. The ring 7 is then slipped over and keyed to the shaft 1 and brought into the position shown in the drawings. The ring nut 8 is screwed down 20 upon the ring 7 and acts through the rings 7, 6, to force the mantles 4, 5, upon the head center taper.

As it is customary to construct the lower mantle 4 of manganese steel and the upper 25 mantle 5 of chilled cast iron, where sectional mantles are used, the lower mantles 4 tend to stretch and become loose upon the head center taper to a greater degree than does the upper mantle 5. As the lower 30 mantle 4 becomes loose upon the center 2, the material being crushed and contacting with the outer surface thereof will tend to rotate this mantle upon the head center 2. This rotation of the mantle 4 causes the 35 helical surfaces at the upper end thereof to slide along the adjacent helical surfaces at the lower end of the upper mantle 5. This relative sliding of the lower mantle upon the surfaces 12 of the adjacent element, 40 causes the mantle 4 to move downwardly or away from the mantle 5 and to become automatically locked upon the taper of the head center 2. If the upper mantle 5 becomes 45 stretched it will rotate upon the tapered outer surface of the head center 2, and the helical surfaces 13 at the upper end thereof will slide upon the similarly formed helical surfaces on the under side of the ring 7. This sliding of the helical surfaces 13 of the 50 mantle 5 upon those of the ring 7 will force the mantle 5 downwardly and away from the locked ring 7, and firmly lock the mantle upon the taper of the head center 2. Since the mantles 4, 5, are formed with a 55 slight amount of clearance between their adjacent ends, the upper mantle 5 will be free to rotate and lock even if the lower mantle 4 has been previously fixed to the center taper.

60 It will be noted that by forming helical surfaces 12, 13, of opposite pitch or inclination relative to planes perpendicular to the crusher axis, at the upper end of each of the mantles 4, 5, the mantles will automatically lock upon the taper of the head center

2 upon relative rotation of the mantles in either direction. The formation of these surfaces 12, 13, as approximate helices furthermore insures surface contact between the adjacent elements at all times.

By locking the mantles 4, 5, to the head center 2 by means at the upper and smaller ends of the respective mantles, the use of interlocking devices between the separate mantles, such as is necessary when the locking of the lower mantle to the head center 2 is from its lower larger end, is avoided. The use of helical surfaces at the smaller ends of the mantles, furthermore causes the mantles 4, 5, to move away from their adjacent forcing elements during locking. As the mantles 4, 5, are generally constructed of very hard material which is difficult to machine, it will be seen that the use of approximate helical surfaces which may be readily formed by casting, is of great importance in that it eliminates necessity of machining other than possibly a slight amount of grinding. By forming helical surfaces 12, 13, of suitable contact area, as 85 distinguished from screw threads, a very strong and serviceable construction is secured.

Although the drawings disclose a crusher head in which a separate head center 2 is 90 employed, it is not intended to limit the invention to such application, as the head center is often formed in one with the crusher shaft 1, especially in the smaller 95 size machines. The mantles 4, 5, may also be combined to form a single mantle without departing from the scope of the present invention. It should be understood that it is not desired to be limited to the exact 100 details of construction shown and described, 105 for obvious modifications will occur to a person skilled in the art.

It is claimed and desired to secure by Letters Patent,—

1. In combination, a tapered head center, 110 and a tapered mantle on said head center, said mantle being formed with a surface at its smaller end adapted to coact with an adjacent element to force said mantle away from said element and onto said head center 115 taper during crushing operation.

2. In combination, a tapered head center, 120 and a tapered mantle on said head center, said mantle being formed with a pair of intersecting surfaces at its smaller end adapted to coact with an adjacent element to force said mantle away from said element and onto said head center taper during 125 crushing operation for relative rotation of said mantle in either direction.

3. In combination, a tapered head center, 130 and a tapered mantle on said head center, said mantle being formed with a helical end surface at its smaller end adapted to coact with an adjacent element to force said man-

tle onto said head center taper during crushing operation.

4. In combination, a tapered head center, and a tapered mantle on said head center, said mantle being formed with a pair of helical end surfaces at its smaller end, said helical surfaces being of opposite pitch and adapted to co-act with an adjacent element to force said mantle onto said head center 10 taper for relative rotation of said mantle in either direction.

5. As an article of manufacture, a tapered mantle formed with a pair of oppositely pitched helical end surfaces at its smaller end.

In testimony whereof, the signature of the inventor is affixed hereto in the presence of two witnesses.
